UNITED STATES PATENT OFFICE.

JOHN B. RUSS, OF SHELTON, AND CHARLES H. POLAND, OF BRIDGEPORT, CONNECTICUT,
ASSIGNORS TO THE ROBERT N. BASSETT COMPANY, OF SHELTON, CONNECTICUT, A COR-
PORATION OF CONNECTICUT.

ELECTROPLATING APPARATUS.

No. 925,599.

Specification of Letters Patent. Patented June 22, 1909.

Application filed August 19, 1908. Serial No. 449,254.

To all whom it may concern:

Be it known that we, JOHN B. RUSS, residing at Shelton, in the county of Fairfield and State of Connecticut, and CHARLES H. POLAND, residing at Bridgeport, in the county of Fairfield and State of Connecticut, have invented a certain new and useful Improvement in Electroplating Apparatus, of which the following is a specification.

10 Our invention relates to electroplating apparatus and more particularly to those of the type wherein the work to be plated is confined in a perforated tumbling drum immersed or partly immersed in an electrolytic solution.

15 The object of our invention is to provide a device of this character having the return current leading from the cathode carried by an independent part insulated from the solution thereby eliminating to a considerable degree the disadvantageous effects due to short circuiting and the tendency of the electrolytic bath to deposit a coating on those immersed parts of the structure made 25 of conducting material.

Another object is to provide a drum supporting frame suitably designed to be suspended from the walls of the solution tank, to carry propelling mechanism for rotating 30 the drum and adapted to be lifted out of the tank to enable the drum to receive and discharge the work; and a further object is to so construct the device in its entirety that it will be strong and durable, efficient in its operation and capable of speedy and convenient manipulation.

With these and other objects in view our invention consists in the details of construction and manner of operation more fully described in the following specification and accompanying drawings in which like reference characters refer to corresponding parts.

40 In the drawings: Figure 1 is a longitudinal section of the apparatus parts thereof being shown in elevation; Fig. 2, a transverse section taken on line x—x in Fig. 1, and Fig. 3, a fragmentary elevation of the end of the device carrying the propelling gear.

Our device primarily comprises the tank A 50 for the electrolytic solution, the frame B for carrying the drum and the propelling gear, and the perforated drum C.

The tank A having end walls a, a' may be

of any suitable construction provided its interior surface is of nonconducting material 55 but we prefer to make the same out of wooden boards.

The frame B consists of the end plates 1, 1' made in skeleton form and rigidly connected at their upper extremities by the rod 2 passed through the pipe 3 and fastened at its ends by the nuts 4, 4' forming a draw bolt connection. The end plates 1, 1' are widened near their upper extremities and are provided on their outer faces with integral feet or hangers 5, 5 and 5', 5' arranged to rest on the top edges of the end walls a and a' respectively. Each pair of hangers is embraced by a pair of downwardly converging guide posts 6, 6 and 6', 6' mounted on the flanges 7, 7 and 7', 7' 70 which latter are bolted to the outside of the end walls a and a' respectively.

Integral with the end plate 1 and projecting from its outer face slightly above and between the hangers 5, 5' is the elongated bearing sleeve 8 bridging the end wall a of the tank, and projecting from the inner side of the end plate 1 is a similar but shorter integral bearing sleeve 9. Both of these sleeves 8 and 9 communicate with each other through 80 the end plate 1 and have their apertured portions in axial alignment to form a shaft bearing for the propelling gear which will herein-after be more fully described. The lower extremities of the end plates 1, 1' are provided 85 with aligned apertures into which are tightly driven the wooden sleeves 10, 10' through which latter passes the stationary cathode rod 11 having its free extremity projecting beyond the end plate 1 and carrying the lock 90 nut 12, and having its opposite extremity bent upwardly outside the end plate 1' to form an arm 13 which is insulated by a vulcanized coating 14. The upper extremity of the arm 13 is flattened and bent outwardly 95 above the wall a' of the tank to present a bracket or base plate to which is fastened the socket plate 15, a close electrical contact being effected by compressing a thin sheet of wire gauze between these two parts. The 100 extremity 16' of a flexible wire 16, leading to the negative electrode of the dynamo and preferably made of twisted strands, is soldered in the socket plate 15.

Journalized to rotate on the inner ends of 105 the wooden sleeves 10, 10' is the perfo-

rated drum C having rigidly attached to its head c a sprocket 17 by means of the bolts 18, the latter having their heads countersunk into the interior surface of the head c of the drum. These bolt heads are buried in beeswax and the countersunk portions are closed by wooden disks 19 driven in to present a flush surface with the inner face of the head c thereby thoroughly insulating the bolt heads. A sprocket chain 20 connects the sprocket 17 with a smaller sprocket 21 which latter is keyed to the inner end of a short shaft 22 journaled to revolve in the bearing sleeves 8 and 9. Keyed to the outer end of the shaft 22 is the gear 23 meshing with a smaller gear 24 which latter is keyed to the shaft 25 journaled in the sleeves 26 and 27 mounted on the bracket 28 bolted to outer side of the wall a of the tank A. Keyed to the outer end of the shaft 25 is the sprocket 29 connected by a sprocket chain (not shown) with the power shaft.

The anodes may be arranged in any well known manner, we prefer, however, to use those of the type which curve inwardly at their lower extremities as indicated at 30 the same being suspended from the supporting rods 31, 31 having their extremities carried by the end walls a, a' of the tank. Mounted on the supporting rods 31, 31 are the clamps 32, 32 in which is detachably secured the positive wire 33 leading from the dynamo.

To operate the apparatus the frame B is elevated by means of lifting chains (not shown) hooked on to the bar 2 until the drum C is clear of the tank. The drum is then charged with the work to be plated and the frame is lowered into the tank to a position midway between the parallel series of anodes 30, 30 the feet 5, 5 and 5', 5' being guided by the posts 6, 6 and 6', 6' until they rest on the end walls 1 and 1' respectively. The drum is thus wholly or partially immersed in the electrolytic solution which passes through the perforated walls of the drum and into contact with the work. The circuit is established between the positive and negative wires 33 and 16 leading from and to the electrodes of the dynamo as soon as the cathode rod 11 becomes awash of the solution in the following manner: from contacts 32, 32 anode supporting rods 31, 31 and anodes 30, through the solution, into the work, and returning passes to the cathode rod 11, through the arm 13 and attached wire 16 back to the dynamo. In our apparatus none of the immersed parts outside of the drum with the exception of the insulated arm 13 are within the circuit and the tendency of these parts to take the deposit or coating is retarded. By eliminating the usual make and break contacts in the return circuit and forming a substantially integral connection between the extremity of the cathode arm 13 and the negative wire 16 a more perfect elec-

trical communication is established thereby producing a superior character of deposit.

The peculiar construction of the frame, which is designed with a view of presenting a structure of minimum lightness, gives a strength and rigidity particularly adapted to firmly maintain its balance and rest solidly on the end walls of the tank when subjected to the weight of the work and severe strains of the driving and propelling mechanism. The arrangement of the feet and guide post does away with all manual assistance when the frame is being lowered into the tank.

Having now described our invention what we claim and desire to protect by Letters Patent is:

1. In an electroplating apparatus the combination with a tank for the electrolytic solution, of a frame comprising end plates rigidly connected at their upper extremities by a lifting bar and provided with integral feet arranged to rest on the walls of the tank, a stationary rod carried by the lower extremities of said end plates, a rotatable drum mounted on said rod, a sprocket rigidly connected with one end of said drum, a shaft journaled in the adjacent end plate having its outer extremity overhanging the end wall of the tank and carrying a gear, a sprocket carried by said shaft on the opposite side of said end plate in vertical alinement with the first mentioned sprocket, a sprocket chain connecting said sprockets, and a driving gear mounted on the outer face of said wall and arranged to mesh with the first mentioned gear whereby when the frame is lifted the driving train will be broken between said gears.

2. In an electroplating apparatus the combination with a tank for the electrolytic solution, of a frame comprising end plates rigidly connected at their upper extremities by a lifting bar and provided with integral feet arranged to rest on the walls of the tank, a stationary rod carried by the lower extremities of said end plates, a rotatable drum mounted on said rod, a sprocket rigidly secured to the face portion of one of the heads of said drum, a short shaft journaled in the adjacent end plate beneath said lifting bar, a sprocket keyed to the inner end of said shaft in vertical alinement with the first mentioned sprocket, a sprocket chain connecting said sprockets, a gear keyed to the outer end of the short shaft overhanging the adjacent end wall of the tank and a driving gear mounted on the outer face of said wall and arranged to mesh with the first mentioned gear whereby when the frame is lifted the driving train will be broken between the said gears.

3. In an electroplating apparatus a tank for the electrolytic solution, a removable frame suspended from the walls of said tank, a stationary cathode member carried by the

- lower extremities of said frame, a drum mounted to rotate around said cathode member, a conductor arm projecting upwardly from one end of said cathode member between one end of the frame and the adjacent wall of the tank, the said arm being independent of said frame and having an outward projection at its upper end above the tank arranged to be permanently secured 10 to the negative wire of the electrical circuit.
4. In an electroplating apparatus a tank for the electrolytic solution, a removable frame resting on the walls of said tank, a drum journaled to rotate between the lower 15 extremities of said frame, a stationary cathode rod mounted in said drum having its outer extremity bent upwardly between one end of the frame and adjacent wall of the tank to form a conductor arm, the said arm being independent of said frame and having its upper extremity flattened and bent outwardly above the walls of the tank to form a clamping base and a socket piece rigidly secured to said base adapted to permanently 20
- embrace the extremity of the negative wire 25 of the electric circuit.
5. In an electroplating apparatus a tank for the electrolytic solution, a removable frame comprising rigidly connected end plates spaced apart and arranged to rest on the walls of said tank, a stationary cathode rod carried by the lower extremities of said end plates, a drum mounted to revolve around said cathode rod, propelling gear for rotating said drum carried by one of said end plates, and a conductor leading upwardly from one end of said cathode rod, the said conductor being independent of said frame and arranged to have its free extremity connected with the negative wire of the electrical circuit. 30 35 40

In witness whereof we have hereunto set our hands this 17th day of August, 1908.
